UNITED STATES PATENT OFFICE.

MILTON L. DODGE, OF NEWBURYPORT, MASSACHUSETTS.

METHOD OF FINISHING SHOES.

Application filed January 8, 1925. Serial No. 1,196.

In the manufacture of shoes, more particularly turn shoes, it is often desirable to close up the crease between the upper and the sole, both to improve the appearance of the shoe 5 and to prevent access of moisture to the stitching, particularly where the stitching has run out well toward the margin of the sole.

According to this invention this is effected by subjecting the edge portions of the sole 10 outwardly of the stitch line between the sole and upper to pressure such as may be exerted by a rapid succession of blows directed thereagainst. This pressure may be exerted primarily against the edge face of the sole so as 15 to thicken it, the increased thickness being localized on its upper face, giving the appearance of a relatively thick sole by the use of stock of ordinary thickness, or it may be directed so as to turn the marginal portion of 20 the sole upwardly into contact with the upper or it may be exerted to flatten and condense the inseam so that the crease between the sole and upper is closed without bending or material thickening of the edge portion of the 25 sole. In any case the operation may be made to flatten the shoe sole and straighten its edge lines. When the sole edge is compacted and thickened it becomes conditioned by this 30 operation to be finished by the usual burnishing tools without the edge trimming operation unless it is desired to impart a beaded or other special configuration thereto. Most 35 advantageously this crease closing operation whether or not thickening or "plumping" of the sole edge is desired may be accomplished 40 by means of a machine of the upper-blocking or pounding-up type, and for this purpose the present invention contemplates the use of a tool for such a machine so formed that it can 45 be used for both the crease closing and the upper-blocking or pounding operations. The tool is so designed that the shoe may be presented in one relation thereto to perform 50 one of these operations and in another relation thereto to perform the other operation, the two operations being performed successively with a single handling of each shoe. Thus the upper is blocked adjacent to the sole so that it takes its final shape and then the 55 edge of the sole is acted upon to cause the crease between it and the upper to be filled.

For a more complete understanding of this invention reference may be had to the accompanying drawings in which

55 Figure 1 is a view in side elevation of a portion

of a pounding machine showing the tool of this invention in position thereon.

Figure 2 is an isometric view of the tool detached.

Figures 3 and 4 illustrate the relative positions of the tool and shoe for the pounding up or upper shaping and the sole plumping or flattening operations, respectively.

Figures 5 and 6 represent transverse sections through the forepart of the turned shoe, 65 showing the condition of the sole before and after the plumping operation, respectively.

Figure 7 is a fragmentary cross section through the edge of a shoe having a thin edge sole.

70 Figure 8 is a similar view showing the crease closing operation being effected by a tool of somewhat different contour from that shown in Figures 1 to 4 inclusive.

Figure 9 is a fragmentary section somewhat similar to a portion of Figure 6, but showing the crease closed without apparent plumping of the sole edge.

Referring to these figures it will be seen that the tool comprises a block 1 having the 80 upper portion of its forward face as at 2 formed concave as a portion of a cylindrical surface extending laterally of the block to conform in general to the curve of an upper adjacent to the sole. The lower edge of this 85 concave surface is defined by a rearwardly extending wall 3 forming therewith a laterally extending slightly rounded shoulder 4. The lower portion of the forward face of the block, as at 5, is formed as a substantially flat 90 face extending downwardly and inclined forwardly from the rear edge of the wall 3 to conform in general to the lower face of the shoe sole. The block is provided on its rear face with means for fixing it to a vibrat- 95 ing member of a blocking or pounding-up machine and for the purpose of illustration it is shown as applied to a machine of the type illustrated in the patent to Knowlton 1,285,740, granted November 26, 1918. This 100 machine, as illustrated in Figure 1 of the present application, is provided with a vibrating arm 10 to the upper end of which the block 1 may be fixed. For this purpose the block 1 is provided with a pair of spaced 105 rearwardly extending flanges 11 between which the arm 10 may pass, the block being fixed in position on this arm by any suitable means such as clamping bolts 12, passed through suitable perforations 13 in the 110

flanges 11 and engaging the arm 10. The arm 10 is fulcrumed at 15 to a portion of the machine frame as 16 and has a rearwardly extending finger 17 which may be pressed into contact with a rapidly rotating cam 18 carried on a shaft 19. This finger may be pressed into contact with the cam by pressure exerted against the block 1 at the outer end of the arm 10 by a shoe held thereagainst and when pressure is exerted in this manner it is evident that a rapid succession of pounding impulses is exerted on the shoe where it is contacted by the block 1. If desired the block 1 may be heated as in the manner disclosed in the Knowlton patent hereinbefore mentioned, an electric heating unit being shown as located at 20 at the rear of the block 1.

For the upper blocking operation the shoe is presented to the block 1 as illustrated in Figure 3, the concave face 2 engaging the shoe upper 25 with the upper edge of the block fitting closely in the crease between the shoe upper and the sole 26. The shoe being presented in this manner and caused to traverse the face 2 of the block, it is evident that the upper is smoothed and shaped to its proper contour, particularly closely adjacent to the upper face of the sole 26. When this smoothing and blocking operation is complete, the operator turns the shoe into the position shown in Figure 4 so as to press the lower face of the sole 26 against the lower inclined flat face 5 of the block which conforms closely to the sole face and so that the shoulder 4 is positioned to bear on the outer edge of the sole toward its upper surface. If the sole is pressed upwardly with some force so that the edge of the sole is acted upon by the shoulder 4, this shoulder exerts a rapid succession of vibrating or pounding impulses on the sole edge inwardly thereof so that this sole edge is compressed and compacted and caused to thicken on its upper surface into close contact with the face of the upper as shown in Figure 6. The engagement of the upper face 5 of the block against the lower face of the shoe sole prevents the sole edge from thickening downwardly and it also acts to flatten the bottom of the sole, straightening its edge line and pounding down the inseam. This action may be clearly understood by reference to Figures 5 and 6. In Figure 5 the sole 26 extends outwardly of the stitch line 30 between the sole and the upper 25 as at 31 and presents substantially the same thickness outwardly of this stitch line as inwardly thereof. The edge plumping operation as carried out by the method hereinbefore described shortens the projecting edge portion 31 of the sole but at the same time thickens it and may bend it upwardly more or less if desired, the thickening taking place locally on the upper face of the sole and causing it to press closely against the upper as shown at 32 in Figure 6. This

action also causes the apparent thickness of the sole to be considerably increased since this thickness is judged by the thickness of the exposed edge of the sole. This also adds to the appearance of the shoe without requiring an excessively heavy sole to be utilized; moreover the pounding and compacting of the sole material at this edge makes unnecessary the usual edge trimming operation, the edge being formed by this plumping operation being in excellent condition for the edge making operation by which the usual bead is formed on the edge of the sole and to receive a superior finish by the edge burnishing tools.

Where thickening of the sole edge is not desired the shoe may be pressed against the face 5 of the block with little upward pressure. The pounding impulses are then exerted in a direction to compact the inseam between the block and the last to an extent sufficient to close up the crease without material thickening of the sole edge, as is shown in Figure 9.

Where a thin edge sole, such as shown in Figure 7 is employed, a tool of modified contour is preferably employed, as shown in Figure 8. In this tool the operating face between the curved face 2 and the flat face 5 comprises a concave cylindrical wall 35 in place of the wall 3 shown in Figures 1 and 4. This curved surface engages the thin marginal portion of the sole in the manner shown in Figure 8 and bends and compacts it against the shoe upper to close the crease therebetween.

The action of the tool in each instance is to close up the crease between the sole and upper and to flatten the inseam, thus helping to prevent access of moisture to the stitching and also to cover any irregularities or unevenness of the parts adjacent to the stitching which is often apparent on turn shoes, particularly where the stitching has run out slightly too far toward the edge of the sole.

Having thus described an embodiment of this invention it should be evident to those skilled in the art that various changes and modifications might be made therein without departing from its spirit or scope as defined by the appended claims.

I claim:

1. The step in the manufacture of shoes which comprises subjecting the edge portion of the fore part of the sole outwardly of the stitch line to vibrating impulses in a direction to close it to the shoe upper and cover the stitches.

2. The step in the manufacture of shoes which comprises subjecting the lower face and outer edge of the sole of a lasted shoe to blows in a direction to close the sole to the upper outwardly of the stitch line between the sole and upper.

3. The step in the manufacture of shoes which comprises subjecting the edge of the

sole of a lasted shoe about said shoe to blows exerted inwardly and upwardly thereon to thicken the sole edge portion and close the crease between the sole and upper outwardly of the stitch line between the sole and upper.

4. The step in the manufacture of shoes which comprises progressively subjecting the edge of the sole of a lasted shoe about 10 said shoe to blows exerted inwardly and upwardly thereon to thicken the sole edge portion and close the crease between the sole and upper and cover the stitches between the sole and upper.
- 15 5. The step in the manufacture of shoes which comprises compressing and thickening the sole edge portion of a lasted shoe in a manner to close the crease between the sole and upper and cover the stitches between the sole and upper. 20

6. The step in the manufacture of shoes which comprises subjecting the lower face and outer edge of the sole of a lasted shoe to blows in a manner to thicken said outer 25 edge on the upper face thereon and close up the crease between the sole and upper and cover the stitches between the sole and upper.

7. The steps in the manufacture of turn

shoes which comprise subjecting the forepart of a lasted shoe adjacent to the sole to rapid 30 blows so directed as to shape and smooth the shoe upper adjacent to said sole, and then subjecting the edge portion of the sole outwardly of the stitch line to repeated blows exerted in a direction to close the crease between it and the shaped upper.

8. The steps in the manufacture of turn shoes which comprise subjecting the forepart of a lasted shoe adjacent to the sole to rapid 35 blows so directed as to shape and smooth the shoe upper adjacent to said sole, and then subjecting the edge portion of the sole to repeated blows exerted in a direction to thicken the sole edge and close the crease between it and the shaped upper and hide the inseam 40 45 stitches.

9. The steps in the manufacture of turn shoes which comprise blocking and smoothing the upper of the turned shoe adjacent to the sole and then thickening the sole edge 50 on its upper face to close the crease between it and the upper.

In testimony whereof I have affixed my signature.

MILTON L. DODGE.
